UNITED STATES PATENT OFFICE.

THOMAS T. CHALONER, OF NEW YORK, N. Y.

AUTOMATIC TRAIN-STOP.

1,361,014.

Specification of Letters Patent.

Patented Dec. 7, 1920.

Application filed June 25, 1918, Serial No. 241,880. Renewed October 6, 1920. Serial No. 415,222.

To all whom it may concern:

Be it known that I, THOMAS T. CHALONER, a citizen of the United States, and a resident of the city of New York, borough of Manhattan, in the county and State of New York, have invented a new and Improved Automatic Train-Stop, of which the following is a full, clear, and exact description.

This invention relates to train stops and particularly to automatic train stops adapted to be carried by the train and arranged to engage and actuate danger arms positioned along the track whereby the stop mechanism will be operated for opening the air brake system of the train when the danger arms have been engaged.

Another object in view is the provision of an overhead appliance which is simple in operation and adapted to be operated at a minimum cost, the same being capable of use on tracks in the open and tracks extending through tunnels.

A still further object in view is to provide an automatic stop structure designed to be attached to a locomotive or other part of the train provided with a sliding arm and other mechanism associated therewith whereby the arm may be moved so as to present what may be termed a short arm when passing through a tunnel and again adjusted for presenting an ordinary long arm when passing on an ordinary track.

In the accompanying drawing:

Figure 1 is a fragmentary sectional view through part of a locomotive cab and also part of a tunnel, and an embodiment of the invention shown applied thereto, certain parts being broken away for better illustrating the structure.

Fig. 2 is a view similar to Fig. 1, except that the arm is shown extended for use outside of a tunnel.

Fig. 3 is a top plan view of the structure shown in Fig. 2.

Referring to the accompanying drawing by numerals, 1 indicates a part of the cab of a locomotive, same being of any desired or preferred structure. Associated with the cab 1 is a pipe 2 forming part of the air brake system, which pipe is supplied with a valve 3 whereby the air brake system may be opened at any time. Valve 3 may be of any desired structure and is preferably provided with an upwardly extending shaft 4 and a handle 5, the handle being operable

by the engineer at any time for setting the brakes or for closing the valve. The shaft 4 has rigidly connected therewith a sleeve 6 which is provided with a clutch face 7 designed to engage the clutch face 8 of sleeve 9, which last mentioned sleeve is rigidly secured by any desired means, as for instance key 10, to shaft 11, which shaft extends upwardly through the rotatable plate 12 carried by the roof of the cab 1. The sleeve 6 is rigidly secured to the shaft 4 by any desired means, as for instance a key, so that when the shaft 11 is rotated, as hereinafter fully described sleeve 9 will be rotated and will transmit motion to sleeve 6 and from thence to shaft 4 and the valve 3 for opening said valve. The shaft 11 extends loosely through the plate 12 which plate is rigidly mounted on a suitable support 13 forming part of the roof of the cab, said plate having a slot 14 through which the rod 15 extends whereby the rod will freely operate and rotate with the plate 12. Rod 15 is pivotally connected to the other end by a bell crank lever 16. The long end of bell crank lever 16 is provided with a slot 17 through which the pin 18 projects, said pin being rigidly secured in any desired manner to the rod 19 slidably mounted on the arms 20 and 21 of the bracket 22. Bracket 22 is rigidly secured to shaft 11 whereby whenever the rod engages a stop 23 in a tunnel or a stop 24 outside of a tunnel shaft 11 will be moved to a certain extent and will open the valve 3 whereupon the brakes will be applied. Ordinarily along a railroad track it is desirable that the various posts and other projections shall be an appreciable distance from the cab of the engine and the various coaches, but in a tunnel a limited space only is provided. To allow the danger stops outside the tunnel to be spaced an appreciable distance from the track the rod 19 is made slidably so as to provide what may be termed a long arm as shown in Fig. 2 for outside work, and a short arm as shown in Fig. 1 for inside or tunnel work. When in either position the action is the same, namely, a partial rotation of the shaft 11 and parts associated therewith for opening the valve 3.

When the parts are in the position shown in Fig. 2 and the engine approaches a tunnel the engineer will pull downwardly upon the rod 15 whereupon the bell crank lever 16 will act on rod 19 for moving the

same to the position shown in Fig. 1 where it is in proper position for engaging stop 23, if said stop is set at danger. After the tunnel has been left rod 15 is pushed up-
5 wardly and the parts moved back to the position shown in Fig. 2 so as to engage the arm 24 if set at danger. After the shaft 11 has been operated by rod 19 striking a danger arm, said rod and danger arm may
10 be moved back to its former position in any desired way, as for instance by operating handle 25 or handle 5. In any event handle 5 must be moved back to close the valve in order to release the brakes. By reason of
15 this construction and arrangement the brakes are automatically applied when passing a danger arm set at danger unless the engineer has arbitrarily operated handle 25 for moving the rod 19 to a position where
20 it will not engage the danger arm. This is done where a relief train is entering a section in which a wreck has occurred or where some relief is desired. In order to prevent any considerable shock to the device
25 or the locomotive and also to prevent breakage rod 19 is provided with a rubber bumper and also the danger arm is provided with a rubber bumper so that the bumpers come together when rod 19 strikes the danger
30 arm. These resilient bumpers not only act to cushion the blow, but will present a removable structure whereby when they are worn more or less new contact members may be provided instead of new rods and new
35 danger arms. In connection with the danger arms it will be of course evident that they may be an ordinary semaphore now in common use positioned to coact with the rod 19, or may be a special arm connected
40 with the ordinary semaphore now in use, or connected with the semaphore system and operated simultaneously with the semaphore.

What I claim is:

45 1. A device of the character described, an air brake valve, a shaft connected with the air brake valve, a bracket having a pair of apertured arms connected with said shaft, a sliding arm positioned in said apertures,

and means for sliding said arm back and forth so as to provide a short and long arm.

2. In a device of the character described, an air brake valve, a shaft connected with the air brake valve through independently movable clutch faces, a bracket carried near 55 the upper end of said shaft, a horizontal slidable rod arranged in said bracket, a bell crank lever mounted on said bracket and connected with said rod for moving the rod to an outer and inner position, and means 60 extending from said bell crank lever to a point accessible to the operator.

3. In a device of the character described, an air brake valve, a shaft connected with the air brake valve, a reciprocating member 65 connected with the upper part of the shaft, and means extending to a point near the air brake valve for reciprocating the reciprocating member.

4. In a device of the character described, 70 an air brake valve, means for manually opening and closing said valve, a shaft, a clutch having one member connected with said shaft and the other connected with said valve whereby when the shaft rotates in one 75 direction the valve will be opened, a bracket arranged at the upper end of the valve, a horizontal sliding rod acting as an operating arm arranged in said bracket, and means for shifting the position of said rod so as 80 to act as a long or a short rod whenever desired.

5. In a device of the character described, an air brake valve, a shaft connected with said valve, a rotatable plate carried by the 85 shaft closing the opening through which the shaft passes when the shaft is arranged on a cab, said plate having a slot, a bracket connected with the upper part of said shaft, a horizontal sliding rod arranged in said 90 bracket, a bell crank lever pivotally connected to said bracket and engaging said rod for shifting the position thereof so that the rod will act as a long and short arm, and an operating rod connected with said 95 bell crank lever extending through the slot in said plate.

THOMAS T. CHALONER.
